TOBACCO BOX AND PACKAGE

Charles E. Sacre, Boston, Mass.

Application May 27, 1939, Serial No. 276,073

3 Claims. (Cl. 206—41.1)

This invention relates to tobacco boxes of the nature employed for packaging smoking tobacco for sale to the consumer, the boxes being used to carry the tobacco during its consumption. Such boxes are relatively deep and narrow and the tobacco is packed somewhat tightly therein within a paper liner. When the tobacco has been removed from the top end of the container, the consumer is obliged to loosen the remaining contents before it will pour from the container. This operation may be performed with a relatively long instrument and, in the absence of such an instrument, the operator usually uses his finger for this purpose. Such use is reasonably satisfactory while the contents are within the reach of the finger, even though the gashing of fingers on the sharp edges of the containers is a common occurrence, but even a long finger cannot reach to the bottom. I am aware that numerous suggestions have been made for remedying this condition but know of none which have been put to practical use except a telescopic two-part container which is objectionable particularly in that the tobacco is more or less exposed to the air and dries out before being wholly consumed. One object of my invention is to produce a relatively simple, inexpensive and superior tobacco container and package.

The container comprising my invention may be constructed in one or two pieces and the tobacco therein is sealed from exposure to the air except at the pouring mouth of the container, and the arrangement and construction are such that a supply of tobacco is always held in close proximity to the pouring mouth. In the one-piece form of the invention, means is provided for holding the tobacco adjacent to the pouring mouth when the bottom end of the container is empty. The two-part form of container embodies two adjacent sections each housing a package of tobacco independently of the other section, and so constructed that the cover can be associated with either section whereby always maintaining the tobacco adjacent to the pouring mouth of the container. A further and important feature of the invention resides in the packaging of the tobacco in two half packs in the container whereby the bottom pack is kept sealed and fresh during consumption of the top half, all forms of my invention being adapted to such use. The production of a novel and improved container of this nature and of a salable package of tobacco or the like embodying such container comprises a further object of the invention.

These and other features of the invention will

be best understood and appreciated from the following description of preferred embodiments thereof selected for purposes of illustration and shown in the accompanying drawings, in which Fig. 1 is a sectional view longitudinally through a tobacco box illustrating one form of my invention,

Fig. 2 is a like view with the contents of the box in reversed position,

Fig. 3 is a perspective view of a spacer element employed within the box,

Fig. 4 is a fragmentary sectional view longitudinally through a tobacco box illustrating another form of the invention,

Fig. 5 is a sectional view longitudinally through a tobacco box illustrating a further form of the invention,

Fig. 6 is a like view of the bottom section of the box with the cover of Fig. 5 applied thereto,

Fig. 7 is a perspective view of the cover in open position,

Fig. 8 is a sectional view transversely through the cover in closed position, and

Fig. 9 is a fragmentary side elevation of the box shown in Fig. 5.

Referring first to the form of invention illustrated in Figs. 1-3, 10 indicates a relatively deep and narrow box or container formed of sheet metal or other suitable material, the bottom 12 being closed and a cover 14 being pivoted thereto at 15. Two independent packages 16 and 18 of tobacco or other packaged product 20 are packed within the container, the closed or bottom ends of the packages being in end to end relation adjacent to the middle of the container.

Cooperating with the two packages 16 and 18 is a spacing element 22 of sheet metal or other relatively stiff material, this element having two fingers 24 spanning and attached to the bottom end of the bottom package 18 and two relatively longer legs 26 extending upwardly along the side edges of the package 16 between the package and the walls of the box.

Upon opening the box, the consumer first uses the contents of package 16, this package being of such depth that the tobacco can easily be reached and loosened with a finger. When the contents of package 16 is consumed, the legs 26 are grasped and pulled out together with the package 18, and these are then reinserted into the box in reversed position as illustrated in Fig. 2 whereupon the legs serve to hold the package 18 in position at the open end half of the box and where the contents can be conveniently reached as was the case with package 16. It
